UNITED STATES PATENT OFFICE

EMIL WILLIAM ZERBEL, OF DETROIT, MICHIGAN

MITER TOOL

Application filed January 5, 1929. Serial No. 330,656.

This invention relates to miter tools.

The main object of the invention is to provide a miter tool for laying off and for cutting miters in moulding and other small work.

Another object of the invention is to provide a nonadjustable improved tool for the purpose named which shall be simple and efficient in operation and which may be inexpensively manufactured.

Other objects of the invention will appear as the disclosure progresses. The drawings are intended to merely indicate a possible embodiment of the invention. It is obvious that the actual needs of manufacture may necessitate certain mechanical changes. It is therefore not intended to limit the invention to the embodiment illustrated but rather to define such limits in the appended claims.

For a more general understanding of the invention attention is called to the drawings. In these drawings like reference characters denote like parts throughout the specification.

In the drawings:

Figure 1 is a top plan view of the miter tool.

Figure 2 is a section on line 2—2 of Figure 1 and,

Figure 3 is a perspective view of the device.

Referring now to the drawings in detail, numerals 1 and 2 designate two arms lying in a common plane and meeting at right angles at the apex 3. At the outer edges of said arms and extending throughout their length are downwardly bent flanges 4 and 5 bent at right angles to said arms. Numeral 6 designates a connecting member extending as a hypotenuse between said arms and lying in the same plane and 7 a flange on said connecting member extending throughout its length and bent at right angles thereto in a direction opposite to the flanges 4 and 5.

It will thus be seen that I have provided a simple, inexpensive and efficient tool for the purpose specified. In operation the flange 7 with the arms 1 and 2 resting on the article to be cut can be placed against the edge thereof and the flanges 4 and 5 can be

used for drawing a guide line for the saw or the saw can be directly guided against said flanges thus providing means for making a straight cut. The device can be cast or stamped from one piece of material.

Having described my invention, I claim:

1. In a tool of the class described, a square comprising two arms lying in a common plane and meeting at right angles, flanges on the outer edges of said arms and extending throughout their length and at right angles to the plane of the arms, a connecting member extending as a hypotenuse between said arms and lying in said common plane, a flange on the connecting member extending throughout its length and bent at right angles thereto in a direction opposite to said first named flanges, said tool being stamped from a single sheet of material.

2. In a tool of the class described, a square comprising two arms lying in a common plane and meeting at right angles, flanges on the outer edges of said arms and extending throughout their length and at right angles to the plane of the arms, a connecting member extending as a hypotenuse between said arms and lying in said common plane, and a flange on the connecting member extending throughout its length and bent at right angles thereto in a direction opposite to said first named flanges.

EMIL WILLIAM ZERBEL.
